UNITED STATES PATENT OFFICE

JOHN L. NILSON AND JOHN F. PRINCE, OF CHICAGO, ILLINOIS

WINDSHIELD-CLEANER-OPERATING MECHANISM

Application filed August 25, 1928. Serial No. 659,245.

Our invention relates to machines for operating the wiper, brush, cleaner, or squeegee employed to clear the vision through a transparent windshield for an automobile, with a driving force generated by said automobile or other power-driven vehicle. The general objects of our present improvement are to further simplify construction, add service functions to simple parts, obviate the liability of disarrangements and temporary stoppages as much as possible, and, in short, to provide increased efficiency with a lowering of costs. And with the above named general objects in view our invention consists in the novel construction, combination and arrangement of parts, all as hereinafter described in detail, illustrated in the accompanying drawing and more particularly pointed out in the appended claims.

In the drawing—

Figure 1 is a longitudinal exterior view of a wiper operating mechanism with the cover for the valve chamber removed to expose the valve and its ports, the wiper or squeegee being partly broken away.

Figure 2 is an enlarged view of a broken away portion of the motor or engine cylinder, and a section through the bearings and valve block taken through the middle portion of which is stepped back to disclose in full lines the air-suction passages leading to the respective ends of the cylinder.

Figure 3 is a section taken substantially on the line 3—3 of Figure 2.

Figure 4 is a longitudinal and side view of a slightly modified form of the reciprocating plate in a position opposite to that in which it is shown by dotted lines in Fig. 1.

Figure 4^a is a detail sectional view taken on line 4^a—4^a, Figure 4, with parts omitted.

Figure 5 is an enlarged rear side view of the rotary valve, the outer side of which is shown in Figure 1.

Figure 6 is a view of the rear end of the bearings and valve block which is projected into the cylinder as in Figure 3, with an intermediate portion broken away and in section to disclose in full lines what is shown by dotted lines in Figure 2, namely, the valve-operating mechanism which shifts the

valve after the end of each piston stroke and in a substantially silent manner.

Figure 7 includes longitudinal and edge views of the lever-operated hexagon with journal ends, one of which is slotted to loosely engage a flat valve tongue, an edge view of the valve, the spring which holds the valve closely against its seat, and an edge view of the closure cap removed from Figure 1 and which serves to hold said spring slightly tensioned against the valve, all separated, and arranged in a position substantially at right angles to the operative position of the valve in the other views to more clearly show the jaw opening 77 and its relation to the tongue 76.

In the several views 2 represents a cylinder which may be made as a section of metal tubing. The ends of this cylinder are closed by heads or caps 3 and 4 which may be attached removably or otherwise in any suitable or ordinary capping manner. In its middle portion the cylinder 2 is provided with a rectangular side opening to receive the lower rectangular portion of the bearing block shown separately in Figure 6. Said side opening is made by making parallel vertical cuts through the side of said cylinder and at least one horizontal cut between said vertical cuts. Between the latter the body of the cylinder is bent out to form a pair of parallel brackets, ledges, lips or fixed jaws 7 and 8, the former engaging the upper portion —6— of the bearing block and the jaw 8 engaging the under-side of the lower rectangular portion —5— of said bearing block, as shown in Figures 1, 2 and 3. The bearing block is secured against sliding movement between said jaws or ledges 7 and 8 by means of screws 9, 10, 11 and 12, or other suitable means. Horizontal threaded bores 13 and 14 (Fig. 6) are also provided in said block. The latter bores are engaged by screws 15 and 16 (Figs. 1, 2 and 3) between the heads of which and the bearing block the windshield frame —17— is clamped as shown in Figure 3. Between the bores 13 and 14 is a somewhat larger bore 18 which is rotatably engaged by an oscillating cleaner-arm 100

shaft 19 to be oscillated by the inclined slots shown in Figure 4 and shown by dotted lines in Figure 1. On the outer end of the shaft 19 and at right angles thereto is mounted a squeegee or cleaner arm 20 for a squeegee or wiper 21, the details of which are not specifically involved in the present improvement. The arm or rod 20 is held at its upper end in a bore 22 which passes transversely through the shaft 19. Said arm is held against longitudinal movement in said bore by a set-screw 23 shown in Figures 1 and 3.

On the inner end of the shaft 19, which projects into the interior of the cylinder 2 as shown in Figure 3, is keyed or secured a flat plate 24 the area of which is indicated by dotted lines in Figures 1 and 4, where said plate is also shown in two opposite positions, or at the respective ends of the piston-strokes. The plate 24 is a double lever or crank in the ends of which are secured laterally projecting studs or crank-pins 25 and 26 which are alternately engaged by slots 27 and 28 (Figs. 1, 3 and 4) and inclines 29 and 30 through and on a plate 31. The ends of this plate are reduced and pass through corresponding slots 33 made through the pistons—34 and 35—and riveted as at 38 to the usual disks 36 and 37, which latter details form no part, specifically, of the present invention, and may be varied in numerous ways to attach the pistons 34 and 35 to the plate 31.

In Figure 4 is added bores 39 and 40 through the plate 31 adjacent to the pistons. These bores, or other suitable openings for like purpose, are to receive hook-ends 42 and 43 of a flexible strip or spring 41 having each of its ends bent twice at right angles to form said hooks, or lugs, 42 and 43 and at the same time space the strip 41 away from the side of the plate 31 to make room for a felt strip 44 or other absorbent material adapted to be soaked with oil to lubricate adjacent parts. The body of the strip 41 is adjacent one side of the plate 31 and its bent out hook or lug portions 42 and 43 engage the opposite side of the plate as indicated by dotted lines in Figure 4, where the oil-carrying strip is omitted while a cross section of it is shown in Figures 3 and 4^a. In Figure 3 the plates 24 and 31 are, for the sake of clearly separating their identities, shown slightly spaced apart, although the plate 24 serves to support the plate 31 against tilting movements. Additional or other supports against such movements are shown provided in a pair of rearwardly projecting fingers 44' and 45 and a lower similarly projecting flange 46, the latter being cut away at 48' to receive the jaw or bracket portion 8.

In the bearing block 5—6 is a valve chamber 46' which is normally closed by a cap 47 tightly pressed into or otherwise held immovably in the outer end of said chamber, as indicated by its position in Figure 3.

Through said cap is a small air-hole 48 which places the valve chamber in communication with the outer air, which communication may also be through a bore 49 which passes entirely through the bearing block from the chamber 46' to the interior of the cylinder 2 which is open to the atmosphere through a slot 50 in the bottom of said cylinder. The length of this slot is substantially that of the reciprocating movements of the pistons and is provided to pass a stud or pin 51 from the interior to the exterior of the cylinder and to permit manual movement of the pistons through said stud. Said stud, or finger-piece, is secured to and projects from a laterally bent out lug portion 52 of the plate 31 and has a threaded outer or lower end provided with a knurled nut 53 which, to prevent accidental movement, through jarring, of the pistons and squeegee, may be tightened against the cylinder. In its normally free condition as in the several views it moves in an exposed position with the pistons and may be operated to free the latter or the valve movement from any temporary clogging during the automatic operation of the squeegee. A fiber washer 54 is preferably placed on the stem 51 between the nut and the cylinder to increase the frictional engagement and hold the squeegee 21 when not in use, out of the line of the operator's vision through the glass, or transparent portion 55, of the windshield.

Automatic operation of the pistons through the suction of the automobile engine is provided through a hose-nipple 56 on the bearing block 5. This nipple, or its equivalent, is connected in any suitable way (usually through a rubber hose not shown) with any portion of the engine where its operation produces a partial vacuum. The bore through the hollow nipple 56, as shown in Fig. 2, leads to a contracted upper end of a threaded bore 56' that is engaged by a threaded valve-stem 57 carrying a knurled head 58, between which and the ledge 8 is interposed a lightly compressed coiled spring 59 to prevent accidental or jarring movement of the valve-stem. The upper end of the latter is pointed in a needle valve portion 60 as shown most clearly in Fig. 2. This needle valve controls a port 61 that communicates with a bore 62. The latter is intersected by and communicates with a valve port 63 leading to a rotary valve 64. The latter is in the form of a circular disk with a segmental cut away portion 65 which provides a space that is always open to the atmosphere or the free air port 49 so that when one end of the cylinder is connected with the suction port the other end of the cylinder will be open to atmosphere. In the inner face of the valve, shown separately in Fig. 5, is an extended curved groove, depression or trough 66. The respective ends of this groove or valve port are placed in communication first

with one end of the interior of the cylinder 2 and then with the other end, through ports 67 and 68, which communicate with the passages through tubes 69 and 70. The latter have their opposite ends placed in communication with the interior of the cylinder 2 through hollow pipe couplings 71 and 72 mounted on the ends or caps 3 and 4, as shown in Figure 1, or in the manner usual with the devices of this kind.

The valve 64 is provided with a boss or hub 73 which is rotatably fitted into a counter-bore 74 in the bottom of the valve chamber 46'. In the outer face of the valve 64 is a somewhat similar bore 75 in which is seated the inner end of a light coiled spring 76 (Figs. 3 and 7) compressed between the valve-chamber cap 47 and the valve 64. From the hub 73 of the valve 64 projects a tongue 76' having a lost motion engagement with a slot 77 in an outer journal end 78 of a hexagon part 79 having an inner journal end 80 that is journaled in a disk or washer 81 (Fig. 3) closing the rear end of a bore 79' (Figs. 3 and 6) in which the hexagon is rotatable. The bore 79' in which the hexagon 79 rotates is intersected by a bore 82 the sides of which are alined with the hexagon 79. Against opposite parallel sides of the hexagon 79 and in said bore 82 are placed balls 83 and 84 which are yieldingly pressed toward each other and against said hexagon by coiled springs 85 and 86 which are held in place by threaded or screw plugs 87 and 88 which normally close the threaded outer ends of the bore 82. From the inner journal end 80 of the hexagon projects a contact pin, arm or lever 89 through which the hexagon is rotated back and forth, or rocked by laterally bent out lugs 90 and 91 on the member 31 (Figs. 3 and 4) which swing the lever sufficiently to place two opposite apexes of the hexagon slightly past dead center and thereby cause the balls 83 and 84 under the pressure of the springs to rotate the hexagon and therewith the valve 64 through the tongue 76' being engaged by the sides of the slot 77. The relation of the slot 77 and the valve-tongue 76' is such that the slot 77 shall rotate, while the hexagon is rotated from its position in, say, Fig. 6, to place opposite angles of the hexagon in horizontal alinement, without moving the tongue 76' until such alinement is reached. Thereafter the balls 83 will move the valve sufficiently to uncover one and cover the other of the ports communicating with the valve-port 66, which takes place, thereby relieving the piston movement of the duty of moving the valves. During that portion of the movements when the lugs 90 and 91 engage the hexagon's lever 89 the squeegee-actuating movement of the plate 31 and its slots 27 and 28, is at rest by providing horizontal extensions 92 and 93 for the lower ends of the slots 27 and 28, through

which slot extensions the respective studs 25 and 26 pass while the lever 89 is being swung.

The operation of our present improvement is as follows: By opening the valve 60, or placing it in the position most plainly shown in Fig. 2 suction takes place through the hose-nipple 56, the passage 62, the port 63, the port 66 in the valve 64 (Figs. 3 and 5), the port 68, the tube 70, and the left hand end of the cylinder (Fig. 1), thus creating a partial vacuum in that end of the cylinder causing the pistons and their connection of Fig. 4, which are shown by dotted lines in Fig. 1, to move to the left. The wrist-pin, or crank-pin, or stud, 26 being in the lower end of the slot 27 (Figs. 1 and 4) and the pin 25 resting on the incline 29, the movement to the left of the piston-connecting plate 31 will cause the pin 25 to be engaged with the oppositely inclined slot 28, the top edge of the latter striking the upper side of the pin with the result that when the pin 26 has risen out of the slot 27 the position of the crank-plate 24 will be reversed or changed from its dotted line position in Fig. 1 to its dotted line position in Fig. 4, thereby effecting approximately semicircular revolution of the shaft 19 and swinging the squeegee to the same extent. By the time the pin 25 has reached the lower end of the slot 28 as in Fig. 4, the lug 91 will have come into contact with the hexagon's lever 89 and swung it sufficiently to cause the balls 83 and 84 to mount and slightly pass the dead center of opposite angle apexes of the hexagon. At this point the pistons will have reached the end of their movement and the pin 25 will be at the right hand end of the horizontal extension 93 of the inclined slot 28 in the Figure 4 position, or in the left hand end of the slot 27 in the Figure 1 dotted line position. The balls 83 and 84 having mounted horizontally alined apexes of the hexagon angles and on parallel inclined sides of the hexagon, the spring-pressure on said balls will rotate the hexagon, which at that moment will have opposite sides of the slot 77 engaged with the tongue 76' of the valve 64. Said valve will then be rotated sufficiently to uncover the port 68 to the atmosphere through the port 49, and port 48 in the valve-chamber cover 47. Simultaneously the port 67 will be closed to the atmosphere and placed in communication with the curved valve-port 66 in the valve 64 and the constant suction port 63 which is diametrically opposite the open air port 49 and leads to the source of suction (not shown) through the passages 62, 61 and 56. The horizontal extensions 92 and 93 of the inclined slots 27 and 28 operate to move the valve while the lever 89 is swung and relieve the suction force from carrying the load of the squeegee while the piston movement is shifting the valve as the projections on the crank members 24 enter the extension just

before the piston member reaches the limit of its movement in either direction and thereby maintains the crank shaft against oscillation during the time that the cranks are operating in the portions 92 and 93 of the slots 64.

5 By grasping the thumb-nut 53 the pistons may be moved by hand and by slightly turning said nut to tighten it against the cylinder 2, the parts shown separately in Fig. 4 and the 10 squeegee shown in Figures 1 and 3 may be held against accidental movements or positions which would annoy the operator of a car or come into line with his vision ahead.

Having thus described our invention, we 15 claim as new and desire to secure by Letters Patent—

1. The combination with a cylinder or casing for a wind shield cleaner operating mechanism, of a reciprocatory member within the 20 casing, a valve responsive in its operation to the movement of said member, said member having oppositely inclined slide contact tracks or surfaces, an oscillatory shaft, a crank on said shaft having parts connected 25 therewith to be engaged by said tracks or surfaces, whereby the shaft will be oscillated when said member is reciprocated, means for imparting reciprocating movement to the said member, and means for maintaining said shaft at rest during a predetermined time in and at a predetermined point of the reciprocation of said member to permit movement of the valve independently of the shaft.

2. In a wind shield cleaner operating 35 mechanism the combination of a casing, of an oscillatory shaft carrying a cleaner member, a crank rocked to and fro by said shaft, a reciprocatory member, a valve responsive in its movement to the movement of said member, said member having slide surfaces 40 thereon which impart rocking movements to said crank when the said member is moved, means for reciprocating said member, and means operating to maintain the shaft at rest 45 and for causing the said member to move for a short distance independently of the shaft and at the limit of movement of said member in both directions to permit movement of the valve independently of the shaft.

50 3. In a wind shield cleaner operating mechanism the combination of a casing, of an oscillatory shaft adapted to oscillate a cleaner member, an oscillatory crank with crank members thereon, a valve responsive 55 in its operation to the operation of the crank, a reciprocatory plate having opposite inclined slots therein arranged end to end and which engage said crank members, the lower 60 ends of said slots being extended in directions substantially parallel with the longitudinal axis of said plate and adapted to receive the crank members, the said extended 65 portions of the slot also serving to hold the crank against oscillation to permit operation

of the valve independently of the crank, and means for reciprocating said plate.

4. Actuating mechanism for a wind shield cleaner which embodies a piston and cylinder, means connected with the piston and extending through the wall of the cylinder and adapted to move said pistons manually, and means whereby the last said means will operate to secure said pistons against movement relative to said cylinder.

5. Actuating mechanism for a wind shield cleaner which embodies a piston and cylinder, said cylinder having an elongated slot through the wall thereof, and a member exterior of the cylinder extending through said slot and connected with the piston whereby said piston may be reciprocated, and means with which said member co-operates for clamping the piston against movement relative to the cylinder and in any position of the piston with respect to the cylinder.

6. The combination of a cylinder or casing, a wind shield cleaner operating mechanism reciprocable therein, said mechanism embodying an elongated actuating member, an oscillatable shaft actuated by the reciprocation of said member, means for reciprocating the member, apertures in said member spaced from each other for a considerable distance in directions lengthwise of said member, a resilient element extending lengthwise of said member, the ends of said element detachably engaging in the respective said apertures, and an absorbent lubricant material disposed between said member and said element and maintained in place by said element.

7. The combination of a cylinder or casing, a wind shield cleaner operating mechanism reciprocable therein, said mechanism embodying an elongated actuating member, an oscillatable shaft actuated by the reciprocation of said member, means for reciprocating the member, apertures in said member spaced from each other for a considerable distance, a resilient element, the ends of said element being hook shaped and seated in the respective said apertures, said ends of the element maintaining the body thereof spaced laterally from said member, and a lubricant holding pad being disposed and maintained between said member and element.

8. In a windshield cleaner operating mechanism the combination of a casing, of an oscillatory shaft adapted to oscillate a cleaner member, a crank connected with the shaft, a reciprocating member in the casing and having oppositely inclined slots arranged end to end and which engage said crank members, a lubricant holding pad secured to the lateral face of said member adjacent and extending over a portion of said slots for lubricating the interengaging portions of said slots and said crank member, and means for reciprocating said member.

9. In a windshield cleaner operating mechanism the combination of a casing, of a reciprocal member therein, a handle connected with said member and extending through the casing for manually moving said member, means whereby said handle will cooperate with the casing wall for locking said member against accidental movement relative to said casing, and means in addition to said handle for reciprocating said member.

10. In testimony whereof we have hereunto signed our names.

JOHN L. NILSON.
JOHN F. PRINCE.
